Atty.

Patented July 14, 1925.

UNITED STATES PATENT OFFICE.

MARSHALL N. JARVIS, OF GILDERSLEEVE, CONNECTICUT.

REVERSING TAPPING DEVICE.

Application filed March 21, 1923. Serial No. 626,456.

To all whom it may concern:

Be it known that I, MARSHALL N. JARVIS, a citizen of the United States, residing at Gildersleeve, in the county of Middlesex 5 and State of Connecticut, have invented a new and useful Improvement in Reversing Tapping Devices; and I do hereby declare the following, when taken in connection with the accompanying drawings and the 10 characters of reference marked thereon, to be a full, clear, and exact description of the same, and which said drawings constitute part of this application, and represent, in— Fig. 1 a broken view, partly in side elevation and partly in vertical section, of one 15 form which a reversing tapping device embodying my invention may assume.

Fig. 2 a detached plan view of the stop-head and the stationary gear of the tap-reversing train.

Fig. 3 a corresponding view, showing the same parts in the positions assumed by them after the shock of reversal has been absorbed, and when the train is reversing the 25 tap.

Fig. 4 a detached, perspective view of the stop-head.

Fig. 5 a corresponding view of the stationary gear of the tap-reversing train.

30 My invention relates to an improvement in reversing tapping devices, the object being to provide such devices, whatever their specific character and construction, with means for absorbing the shocks developed 35 at the instant of reversing the tap, so as to avoid breaking the same and racking the device.

With these ends in view, my invention 40 consists in a reversing tapping device provided with a shock-absorber.

My invention further consists in a reversing tapping device having certain details of construction and combinations of parts 45 as will be hereinafter described and particularly pointed out in the claims.

In carrying out my invention, as herein shown, I have applied it to a reversing tapping device, comprising a chambered body 6, a shank 7 and a chuck 8, in which latter a 50 tap may be secured by a set-screw 10. It will be understood that, as usual in such devices, the chambered body 6 and shank 7, though not integral, are connected so as to constantly turn in the same direction, while the chuck 8 turns with them in the 55 forward direction, but in the reverse direc-

tion for reversing the tap 9. The reversing of the chuck is done in the usual manner by a train of planetary gears located within the body 6 and not necessary to show 60 or describe because not constituting a part of my present invention, with the single exception of the stationary gear 11, the concentric sleeve 12 of which projects upward through the body 6. As an illustration of 65 a reversing tapping device of the character now being described, I refer to United States Patent No. 1,010,743, dated December 5, 1911, but I do not limit the application of my invention to such a device as 70 shown in the said patent, nor to any particular reversing tapping device.

In carrying out my invention, as herein shown, the sleeve 12 of the gear 11 is formed with two oppositely-located, wedge-shaped 75 lugs 13, which enter and have limited movement in oppositely-located, segmental notches 14, formed within an annular stop-head 15 provided with a tubular arm 16 and having bearing, as shown in Fig. 1, directly 80 upon the flat top of the body 6. The arm 16 receives a stop-rod 17 secured in place by a pin 18 and designed to engage with some fixed portion of the drill-press, lathe, or other machine in which the tapping device 85 is being used. The function of the stop-head 16 and its rod 17 is to prevent the rotation of the gear 11, whereby the chuck is 90 reversely driven in the usual manner of reversing tapping devices of the prior art. 90

To eliminate the shock incident to reversing the chuck and tap, and so reduce to the minimum the danger of breaking the tap and the racking of the entire device, I provide the gear 11 with the lugs 13 and the stop-head 15, with segmental notches 14 for the reception thereof, as already described. Between the notches 14, the stop-head is formed with segmental grooves 19 for the reception, respectively, of two helical, shock-absorbing springs 20, each abutting at one end upon a pin 21 and having their opposite ends engaged with the faces 22 of the lugs 13, the opposite faces 24 whereof engage with the end-walls 25 of the notches 14. On the other hand, the faces 22 of the said lugs, after the compression of the springs 20, are brought to bear upon the opposite end-walls of the notches 14. 105

Under the construction described, the operation is as follows:

In the forward drive of the tapping de-

vice, that is to say, when the tap 9 is being threaded into the work, no operating strain is imposed upon the gear 11, nor upon the stop-head 15 and its arm 17. At this time, 5 the faces 24 of the lugs 13 bear upon the end-walls 25 of the notches 14 against which they are lightly held by the uncompressed shock-absorbing springs 20. The instant, however, the tapping device is drawn away 10 from the work, or the work drawn away from it, the tap-reversing train of the device is brought into play in the usual manner with the effect of almost instantly reversing the direction of rotation of the chuck 8 and 15 tap 9. This reversing action immediately throws strain upon the gear 11, the stop-head 12 and the rod 17, whereby the said gear is oscillated within the stop-head 14 against the tension of the shock-absorbing 20 springs, which take up the shock of this sudden reversal before the stop-faces 22 of the lugs 13 are brought to a bearing upon the end-walls 25 of the said notches. Strictly 25 speaking, the actual reversing of the chuck and tap does not begin to take place until the two springs are nearly compressed, or compressed to the limit of the compression permitted. This momentary cushioning at the time of reversal, due to the presence of 30 the shock-absorbing springs, prevents the brittle tap from receiving what amounts to a blow at the time of reversing its movement and incidentally prevents the racking of the entire reversing mechanism.

35 I am aware that, broadly speaking, it is old to provide a reversing mechanism with

shock-absorbing means for cushioning its reversing action, and do not claim such shock-absorbing reversing mechanism broadly, but only as applied to portable reversing 40 tapping devices.

I claim:

1. A portable reversing tapping device having a body, a shank and a chuck, a stationary gear located within the said body 45 and provided with a lug, a stop-head carrying a stop-arm and formed with an abutment, and a spring located within the said stop-head and coacting with the said lug and abutment for cushioning the shock consequent upon reversing the direction of the rotation of the chuck.

2. A reversing tapping device having a body, a shank and a chuck, a stationary gear located within the said body and provided 55 with a projecting sleeve having two oppositely-located lugs, a stop-head carrying a stop-arm and formed with two segmental notches for the reception of the said lugs, faces of which co-act with end-walls of the 60 said notches, and two shock-absorbing springs located within the said stop-head and co-acting with the said lugs for cushioning the reversing of the chuck.

In testimony whereof, I have signed this 65 specification in the presence of two subscribing witnesses.

MARSHALL N. JARVIS.

Witnesses:

CHARLES L. JARVIS,
FRANK C. BARKER.
